Primary Examiner — Selina Sikder(74) *Attorney, Agent, or Firm* — Fredrikson & Byron, P.A.(57) **CLAIM**

An ornamental design for a wall mountable control panel, as shown and described.

DESCRIPTION

FIG. 1 is a perspective view of the wall mountable control panel.

FIG. 2 is a front elevation view thereof.

FIG. 3 is a right side elevation view thereof.

FIG. 4 is a left side elevation view thereof.

FIG. 5 is a top plan view thereof; and,

FIG. 6 is a bottom plan view thereof.

The rear elevation view of the wall mountable control panel is hereby disclaimed and forms no part of the claimed design.

The broken lines in the drawings depict portions of the wall mountable control panel in which the design is embodied that form no part of the claimed design.
